UNITED STATES PATENT OFFICE.

FRANK J. JOHNSTON, OF SACRAMENTO, CALIFORNIA.

ROTARY TARGET.

No. 884,663.

Specification of Letters Patent.

Patented April 14, 1908.

Application filed October 2, 1907. Serial No. 395,560.

To all whom it may concern:

Be it known that I, FRANK J. JOHNSTON, citizen of the United States, residing at Sacramento, in the county of Sacramento and State of California, have invented new and useful Improvements in Rotary Targets, of which the following is a specification.

My invention relates to targets, and especially to targets for use in shooting-galleries 10 and other places of amusement.

The object of the invention is to provide a simple and unique form of entertainment in the nature of a revolving target wherein the skilful operator, by hitting the bull's eye, 15 will set a pointer or target in motion; and on the pointer coming to rest, it will indicate a certain prize that he is entitled to.

The invention consists of the parts and the construction and combination of parts as 20 hereinafter more fully described and claimed, having reference to the accompanying drawings, in which—

Figure 1 is a front elevation of the target. Fig. 2 is a central vertical section. Fig. 3 is a 25 detail view of the target rotating mechanism.

A represents a disk, preferably of sheet-metal, and bearing suitable rings, or other indications of a target. This disk is mounted loose on a hollow shaft or spindle 2, the 30 latter being appropriately journaled to rotate in suitable bearings, as 3. Outside of the target A is an annular disk 4, shown as divided by radial lines into certain spaces which may be consecutively numbered, as 35 here shown, and these spaces may be variously colored, if desired; and each space will represent a certain prize, as, for example, so many cigars, in case the pointer 5 which is carried by the target should come to rest 40 over any particular space.

The idea of the invention is that the marksman, endeavoring to hit the center of the target, will, in the event of the bullet passing through the tube 2, strike against some obstruction or trigger arrangement which will momentarily set the target in motion and cause it to spin until the target and pointer will come to rest, and the pointer 5 will stand over some one of the several spaces on the 50 annulus 4. The pointer carries a spring or brake member 6 which is adapted to engage lightly with successive pins 7 on the annulus and properly retard the rotative movement of the target and finally bring it to rest with 55 the pointer squarely over some one of the spaces on the annulus.

Any appropriate mechanism may be employed to produce the periodical rotation or spinning of the target. As here shown, the tubular shaft 2 carries two loose pulleys or drums 8—8' which are preferably fastened together so as to turn in unison. 9 is a ratchet member fastened to the tube 2, and the drums are normally locked to the ratchet by means of the pawl 10 on one of the drums. 60

Arranged in the path of the bullet at the inner end of the tube 2 is one end of a bell-crank lever 11. The opposite end of the trigger or bell-crank 11 is adapted to engage, as here shown, with the teeth of a gear 12; 70 which gear meshes a corresponding gear 13 on the side of the ratchet 9. A counterweight 14 is attached to a rope or cord 15 which is wound up on the drum 8. When the bell-crank or trigger 11 is engaged with the gear 12, the latter cannot turn, and being in mesh with the gear of the ratchet, and the drums being locked to the ratchet by the pawl 10, the apparatus is held stationary. 75 Assuming the cord 15 to be wound up on its drum, if the trigger 11 is tripped so as to disengage it from the gear 12, thereby throwing the trigger into dotted line position, Fig. 2, the counterweight will act to set the drum and the shaft 2 in motion. 80

In order to transmit rotative motion from the spindle to the target A any appropriate form of connection may be employed, as, for example, the pawl 16 on the hub of the target engaging with ratchet 17 which is fixed 90 on the shaft; it being understood that the pawl and ratchet arrangement 16—17 is such that the falling weight causes the parts to interlock. But the moment the shaft 2 comes to a standstill the target will continue 95 to spin with the pawl 16 riding free over the ratchet 17. The spinning movement of the target continues until the spring brake 6 acting on the pin 7 brings the target to rest with the pointer 5 resting over one or other of the divisions on the annulus 4. The trigger 11 is maintained in normal engagement with the star-wheel or pinion 12 by gravity or otherwise. 100

Any appropriate means may be employed 105 to wind up the cord 15 and raise the weight ready for the next operation. As here shown, a cord 18 is wound up on the drum 8' in a reverse direction to the cord 15, and this cord extends forward to any suitable point 110 within convenient reach of the operator, so that after the weight has fallen, by pulling

on the cord 18 the weight will be lifted, with the pawl 10 riding free in its backward movement over the ratchet 9. Whenever the tension of the cord 18 is slackened, the pawl 10 engages the ratchet 9 and holds the weight.

It is possible that the invention may be practiced in various forms without departing from the principle thereof, and I do not wish to be understood as limiting myself to any specific mechanism, or special mode or means of spinning the target.

Having thus described my invention, what I claim and desire to secure by Letters Patent is—

15 1. The combination with a fixed sub-divided disk, a rotary target and a hollow spindle upon which the same is loosely mounted, of a drum loose on said spindle, a ratchet member fixed to the spindle, and provided 20 with a gear on its side, a gear journaled at right angles to the axis of the first-named gear, and the bell-crank lever having one arm to engage the teeth of the second named gear and having another arm normally disposed proximate to the inner end of said 25 spindle and in the range of action of a projectile passing through said spindle whereby the lever is actuated to release the second-named gear from its locked position, means 30 for rotating the drum, means for communicating the rotation of said drum to the first-named gear, and means connecting the target with the hollow spindle, said last-named means allowing the target to rotate 35 relative to said fixed disk.

2. The combination with a rotary target, a hollow spindle upon which the same is loosely mounted, and a fixed disk, said disk and target having a movement one relative 40 to the other, of mechanism for spinning the target, said mechanism being actuated by a projectile passing through the spindle, and

comprising a bell-crank lever having one arm arranged close to the inner end of said spindle and in the path of said projectile, a 45 counterweighted member loose on the spindle, a member fixed to said spindle and inter-engaging connections between said fixed member and loose member, a gear wheel mounted on a vertical axis and a gear member 50 on said fixed member and in mesh with said gear wheel, said bell-crank lever having a second arm which is designed to engage said gear wheel to hold the members locked, and to release said wheel when the lever is 55 tripped by the impact of the projectile, and engageable connections between the target and the hollow spindle.

3. The combination with a rotary target, a hollow spindle on which the same is loosely 60 mounted, and a fixed disk past which the target is adapted to rotate, of means for spinning the target operated by a bullet passing through said spindle, said means including a bell-crank lever pivotally mounted near the 65 inner end of the spindle and having one arm normally disposed in the range of action of the bullet, a gear wheel normally engaged with the other arm of said lever, a ratchet member fixed to the spindle and having a 70 gear with which said gear wheel is in mesh, a drum loosely mounted on the spindle and a pawl carried by said drum and adapted to engage said ratchet member, a pawl on the hub of the target, a ratchet fixed to said 75 spindle and engaged by said pawl, and means for retarding the rotation of the target.

In testimony whereof I have hereunto set my hand in presence of two subscribing witnesses.

FRANK J. JOHNSTON.
